CLAIM

We claim the ornamental design for a data capture device, as shown and described.

DESCRIPTION

FIG. 1 is a top perspective view of a data capture device; FIG. 2 is a bottom perspective view thereof; FIG. 3 is a top view thereof; FIG. 4 is a bottom view thereof; FIG. 5 is a first side view thereof; FIG. 6 is a second side view thereof; FIG. 7 is a rear view thereof; and, FIG. 8 is a front view thereof.
Broken lines of a particular embodiment are for purposes of illustrating environment and form no part of the design claimed in that embodiment.
